W. G. NORTHRUP,
TILTING HEADLIGHT,
APPLICATION FILED OCT. 5, 1917.

1,437,542.

Patented Dec. 5, 1922.

Inventor
William G. Northrup

By Chester N. Braselton
Attorney

UNITED STATES PATENT OFFICE.

WILLIAM G. NORTHRUP, OF TOLEDO, OHIO.

TILTING HEADLIGHT.

Application filed October 5, 1917. Serial No. 194,955.

To all whom it may concern:

Be it known that I, WILLIAM G. NORTHRUP, a citizen of the United States, residing at Toledo, in the county of Lucas and 5 State of Ohio, have invented certain new and useful Improvements in Tilting Headlights, of which I declare the following to be a full, clear, and exact description.

This invention relates to improvements in 10 automobile headlights, of the type which are provided with a tilting reflector, which may be tilted so as to direct the beam of light downwardly upon the ground in front of the automobile. The principal object of my invention is to provide an improved mounting 15 for the reflector within the headlight casing, which is of such a nature as to lend itself to the ready production of these headlights in large quantities at small expense and has 20 novel advantages when assembled. A further object of my invention is to provide an improved mounting for the reflector in the casing, which will be substantially rattle-proof.

25 Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended 30 claims. A structure constituting one embodiment of my invention, which may be the preferred, is illustrated in the accompanying drawings forming a part hereof in which:

40 Figure I is a vertical, sectional view taken through a headlight embodying my invention.

Figure II is a view in front elevation of 45 a headlight embodying my invention with the lens and ring removed.

Figure III is an enlarged, fragmentary, detail, sectional view, taken substantially on the line III-III of Figure II, and

50 Figure IV is a detail, fragmentary, plan view showing one member of the reflector hinge.

In the drawings, similar reference numerals refer to similar parts throughout the several views, and the sectional view is taken

looking in the direction of the little arrows 55 at the ends of the section line.

Considering the numbered parts of the drawings, I have shown a headlight comprising a casing 10, the front end of which is closed by lens 11 carried by ring 12, which 60 is secured to the casing 10 in the usual manner. A reflector 13 of the usual parabolic type is mounted within said casing so as to tilt therein, the upper forward edge of the casing 10.

65 Brackets 14 are secured to the upper forward edge of the casing 10 by means of the rivets 15, and extend downwardly and carry at their lower ends a pintle 16. Yoke 17 is riveted to the upper forward edge of the 70 reflector, by means of the rivets 18, and the forward ends 19 of said yoke are wrapped around and embrace the pintle 16. A leaf spring 20 is riveted to the yoke 17 at 21 and is provided with a laterally bent end 30, 75 which engages the pintle 16 between the pintle bearings 19. The co-acting parts of the hinge may, of course, be reversely connected to the casing and reflector respectively and the leaf spring 20 may be arranged in any 80 manner effective to frictionally prevent relative motion of the reflector relative to the casing at its pivoted connection therewith to absorb vibrations and prevent rattling when the device is used on a motor vehicle. A 85 lug 22 is secured to the lower part of the reflector, at a point substantially diametrically opposite the hinge above described, and the forward end of a wire 23 is connected to said lug 22, said wire passing out of the 90 casing 10 through a tube 24 secured in a boss 25 formed in the casing 10. A connector 26 is carried by the casing 10 and connected by wires 27 with the socket 28, carried by the reflector 13, a light bulb 29 being disposed 95 in said socket 28 in the usual manner.

From the description of the parts given above, the operation of this device should be very readily understood. The reflector is tilted within the casing 10 by means of 100 the wire 23, the reflector being shown in full lines in Figure I in its normal position, in which it throws a substantially horizontal beam of light, and being illustrated in dotted lines in the position to which it is 105 tilted in order to throw a deflected ray of light downwardly upon the ground. The wire 23, may be manipulated in any desired

manner. The means for tilting the reflector forms no part of my present invention, which has to do with the mounting of the reflector within the casing. Yoke 17 forms 5 substantially a part of the reflector 13 and pivots on the pintle 16, carried by the brackets 14 depending from the casing 10, so that the reflector 13 is hinged to the forward end of the casing 10 at the upper 10 part thereof, said hinge being substantially in the vertical plane, which contains the axis of the reflector.

The hinge formed by the yoke 17 and the pintle 16 cause the reflector to tilt on a horizontal axis defined by the pintle 16 and there can be no lateral twisting of the reflector within the casing. This hinge construction lends itself particularly to the production of these headlights in large quantities, as it 15 is not necessary to position this hinge as accurately as would be the case if trunnions were used at the sides of the reflector. In order to make the hinge at the top of the reflector substantially rattle-proof, a 20 leaf spring 20 is provided, which bears upon the pintle 16, between the bearings 19, and holds the pintle tightly against its bearings in the ends of the brackets 14, so that it cannot rattle. The provision of a single hinge 25 connecting the upper forward edge of the reflector with the upper forward edge of the casing is also desirable because the reflector can be normally disposed closer to the lens, and the total depth of the casing can 30 be lessened, since the reflector swings from its upper edge, and, in swinging from its normal position to its tilted position, swings 35 entirely away from the lens.

I am aware that the particular embodiment of my invention, which I have here 40 shown and described, is susceptible of considerable variation without departing from

the spirit thereof, and, therefore, I desire to claim the same broadly, as well as specifically, as indicated by the appended claims. 45

Having thus described my invention, what I claim as new and desire to secure by Letters Patent, is:

1. In a device of the class described, a headlight having in combination a casing or 50 supporting member, and a reflecting member, a pair of brackets connected with the upper forward edge of one of said members, a pintle carried by said brackets, a hinge element secured to the upper forward edge 55 of the other of said members and having a bearing on said pintle, and a spring carried by one of said members and operative to restrain all movement between said pintle and said hinge element to thereby absorb 60 vibrations and avoid rattling.

2. A device of the class described, comprising the combination of a casing; a pair of brackets depending from the upper forward edge of said casing; a pintle carried 65 by said brackets; a reflector mounted in said casing; a hinge member secured to the upper forward edge of said reflector, and having a bearing on said pintle; a leaf 70 spring secured to said reflector, and having its free end bearing on said pintle; and means for tilting the reflector in the casing.

3. A device of the class described, comprising the combination of a casing; a pintle carried thereby and extending horizontally; a reflector; a member carried by said reflector and having a bearing on said 75 pintle at separated points; a spring secured to said reflector and having its free end bearing on said pintle between said points; 80 and means for tilting said reflector.

In testimony whereof I affix my signature.

WILLIAM G. NORTHRUP.
